(57) **CLAIM**

I claim the ornamental design for a video camera, as shown and described.

DESCRIPTION

FIG. 1 is a top, left and front perspective view of a video camera.

FIG. 2 is a bottom, right and rear perspective of the video camera illustrated in FIG. 1.

FIG. 3 is a top plan view of the video camera illustrated in FIG. 1.

FIG. 4 is a front elevation view of the video camera illustrated in FIG. 1.

FIG. 5 is a rear elevation view of the video camera illustrated in FIG. 1.

FIG. 6 is a bottom plan view of the video camera illustrated in FIG. 1.

FIG. 7 is a right side elevation view of the video camera illustrated in FIG. 1.

FIG. 8 is a left side elevation view of the video camera illustrated in FIG. 1.

FIG. 9 is a left side elevation view of the video camera illustrated in FIG. 1 with the USB plug in an extended position; and,

FIG. 10 is a front elevation view of the video camera illustrated in FIG. 1 with the USB plug in an extended position. The portions of the video camera in broken lines are shown for illustrative purposes only and form no part of the claimed design.
